PARTITIONING DEVICE FOR AUTOMOBILE GLOVE COMPARTMENT

Philip Ershler, Washington, D. C.

Application March 23, 1951, Serial No. 14,602

Term of patent 14 years

(Cl. D14—6)

To all whom it may concern:

Be it known that I, Philip Ershler, a citizen of the United States of America, residing at city of Washington, District of Columbia, have invented a new, original, and ornamental Design for a Partitioning Device for Automobile Glove Compartment, of which the following is a specification, reference being had to the accompanying drawing, forming a part thereof.

Figure 1 is a front elevational view of a partitioning device embodying my new design;

Figure 2 is a top plan view thereof;

Figure 3 is a side elevational view of the same;

Figure 4 is a rear elevational view thereof; and

Figure 5 is an enlarged perspective view of the device.

I claim:

The ornamental design for a partitioning device for automobile glove compartment, as shown.
PHILIP ERSHLER.
